ISIDORE KLEIN, OF NEW YORK, N. Y

SAFETY-ENVELOP.

No. 902,301.

Specification of Letters Patent. Patented Oct. 27, 1908.

Application filed November 13, 1906. Serial No. 343,194.

To all whom it may concern:

Be it known that I, ISIDORE KLEIN, a citizen of the United States, residing at New York city, in the county of New York and State of New York, have invented certain new and useful Improvements in Safety-Envelops, of which the following is a specification.

My invention relates to envelops and more particularly to envelops which cannot be opened without damage and resultant detection.

The invention consists in a certain form of blank, and an arrangement of sealing flaps such as will be later described, and its object is to provide an envelop whose flaps when sealed cannot be opened by the use of steam or the insertion of a knife blade or other instrument beneath them without so badly damaging the envelop that the unauthorized breaking of the inclosure is plainly evident.

I have shown my invention in the accompanying drawing, wherein

Figure 1 is a rear view of the envelop sealed. Fig. 2 is a rear view of the envelop unsealed. Fig. 3 is a rear view showing the envelop with one of the flaps opened out to show certain details thereof. Fig. 4 is a plan of the blank from which the envelop is to be made.

Like numerals throughout all the figures indicate like parts.

2 designates that portion of the blank which forms the front of the envelop.

3 is the upper flap, which is usually used in envelops.

4 is the lower flap, and 5 and 6 are the two side flaps. The lower flap 4 instead of being pointed and extending to the middle of the envelop when folded, is of sufficient depth at its side edges to extend up to the fold of the top flap 3. A triangular shaped portion may be cut out in its center with edges 4' which, when the flap is folded extend downward parallel with the upper edges of the side flaps 5 and 6. The edge 4' is not in alignment with the edges of the side flaps, as they are before sealing, but project a slight distance above said flaps as shown in Figs. 2 and 3.

It will be evident that the rear flap may extend up to the fold of flap 3 along its entire upper edge, and it is also evident that the entire space designed to be covered by the flap 3 might be gummed instead of just

simply the margin 4", but I deem it preferable to save the weight in this way and to have the gummed margin 4" correspond in shape with the margin of the flap 3. Instead of having the rear flap gummed as at 4" the upper flap 3 might be gummed along its inner margin with exactly the same effect and I wish it understood that I regard such a transposition of the gum as entirely equivalent to the use of the gum on the rear flap and as entirely within my invention. The margin of this flap 4 is gummed on its outside face as at 4" for the attachment of the margin of the upper flap 3. The end flaps 5 and 6 are substantially of the same form as the usual end flaps of envelops except that along their upper edges they are bent backwardly to form the auxiliary flaps 5' 6'. The inner surface of the flaps 5 and 6 has gum or other adhesive placed along the margins as at 5" 5'", 6" 6''. By means of these gummed margins the flaps are pasted down upon the back flap 4 in the position as shown in Fig. 2. It will be seen that the end of flap at 6''' projects up under the extreme end of the flap 5 and is protected thereby.

In sealing the envelop, the flap 3 is brought down and by means of the gum 4" its margin is attached to the back flap 4. Then the folds or auxiliary flaps 5' 6' are moistened and folded over on to the outer face of the margin of flap 3 as shown in Fig. 1. It will now be seen that counting from the bottom there are three gummed faces to be attacked before any opening can be made into the envelop by attempting to raise the flaps 5 and that the flap 3 is not only held down by the gummed margin 4" but that it is protected by the auxiliary flaps 5' 6'. It is also to be noticed that were the flaps 5' 6' to be raised the edge of the top flap 3 would be protected by the edges of the side flaps 5 and 6 to the extent of not allowing a knife blade to be inserted under the edge of the flap 3, or preventing the insertion of any round instrument, as pencil or pen holder, which by its rotation might raise the flap 3. This is a most important point as it has been found in practice that the top flap 3 being on a level with the main portion of flaps 5 and 6 absolutely prevents the insertion successfully of any instruments for opening the flap 3. Again, the auxiliary flaps 5' 6' protect the gum attaching flap 3 to 4 and thus prevent steaming the letter open. The fact

that the rear flap 4 also extends up to a distance beyond the margin of flap 3 is also of importance as an instrument inserted under the side flaps 5 and 6 must first open the 5 gummed margin 5" 6", is then met by the gummed margins 5" 6" and lastly it is met by the gummed margin 4".

Another point of value is the fact that the gummed margin 4" of the back flap 4 extends up to the edge of the envelop and that 10 the auxiliary flaps 5' 6' also extend up to the extreme upper edge of the envelop. Thus the top flap 3 is protected from the insertion of a knife blade not only at its lower 15 corner but along its whole extended margin. With ordinary envelops it is possible to insert a pencil or other round object along the upper edge between the sealing flap and the main portion of the envelop and then by 20 rotating the pencil or roller to open the flap 3 without in any manner marring the envelop, or at any rate open it sufficiently that the contents may be examined or drawn out. This is not the case with envelops made according to my invention as it is impossible 25 in the first place to insert any instrument between the flap 3 and the main portion of the envelop by raising the auxiliary flaps and also because with the double holding 30 surface given by the margin 4" and the auxiliary flap there can be no lifting of the upper flap away from the gummed surface but only a tearing of the flap which is, of course, immediately shown. As an additional protection against any tampering 35 with the envelop by lifting the side flaps 5 and 6, I provide the bottom flap 4 with two inwardly turned flaps 4'" which are gummed on their outside faces and by this gum are 40 attached to the inside face of part 2 of the envelop, thus forming a sort of pocket of the rear flap and the front of the envelop. When these auxiliary flaps 4'" are used, even if the side flaps were raised, it would 45 still be necessary to detach the rear flap from the front face of the envelop. It is to be also noted that the rear flap being covered by the side flaps 5 and 6, it is impossible to steam open the auxiliary flaps 4'", they being 50 fully protected by the side flaps. The envelop is so securely sealed by reason of these different gummed portions that as so far described it is practically impossible to open it without mutilating it or without cutting off one edge.

As in many offices, a small pointed instrument is used for inserting under the edge of the flap and cutting through it when opening letters, it is necessary to provide means 60 for the insertion of said instrument. I do this by cutting away the rear flap as at 4'" at its junction with the side flaps and the face of the envelop. Through the opening thus formed at each lower corner of the en-

velop, an instrument may be inserted to cut 65 through either at the side of the envelop or at the bottom edge thereof.

My invention is simple and may be cheaply made, and does not require any wide variation in the form of envelop machinery at 70 present in use. It is thoroughly effective in operation and prevents any unauthorized tampering with the envelop without detection.

Having described my invention what I 75 claim is:

1. An envelop having an upper sealing flap and side flaps, a lower flap extending upwardly beneath the side flaps and having a gummed margin projecting beyond the 80 upper edge of the side flaps along its entire length adapted to engage with the margin of the sealing flap when the latter is sealed down, said side flaps being gummed to the outer face of the lower flap and having free 85 auxiliary flaps extending along the whole length of their upper edges and directly attached to and in one piece with the upper edges of the side flap, said auxiliary flaps being provided on their under surface with 90 an adhesive and being adapted to cover and be attached to the outside margin of the sealing flap along its whole length when the latter is sealed.

2. An envelop having an upper sealing 95 flap and side flaps, a lower flap extending upwardly beneath the side flaps projecting beyond the same along the entire length thereof and having a gummed margin adapted to engage with the margin of the sealing 100 flap along its entire length when the latter is sealed down, auxiliary flaps extending along the entire length of the side edges of the lower flap, folded inwardly and attached to the inside face of the front of the envelop, 105 said main side flaps having an upper margin continuous with and abutting against the entire length of the lower edge of the sealing flap when the latter is sealed, and being provided with auxiliary flaps extending the 110 entire length of said upper margin directly attached and formed in one piece with the side flaps, provided on their under surface with an adhesive adapted to be folded down 115 to cover and be attached to the outside face of the lower margin of the sealing flap.

3. A blank for envelops having the face portion 2, the sealing flap 3, the lower flap 4 having the gummed margin 4", and the two end flaps 5 and 6 having the gummed margins 5" 5'", 6" 6", provided with the auxiliary flaps 5' 6' gummed on their inner surfaces for attachment to the sealing flap 3, when the envelop is folded, substantially as described.

4. A blank for envelops having the face portion 2, the sealing flap 3, the lower flap 4 having the gummed margin 4" and the aux-

iliary gummed side flaps 4", and the two end flaps 5 and 6 provided with the auxiliary flaps 5' 6' gummed on their inner surfaces for attachment to the sealing flap 3, 5 when the envelop is folded, substantially as described.

In testimony whereof, I have signed my

name to this specification in the presence of two subscribing witnesses, this 18th day of January 1906.

ISIDORE KLEIN.
